UNITED STATES PATENT OFFICE.

JESSE K. PAINTER, OF JULESBURG, COLORADO.

DESIGN FOR A GRASS AND WEED CUTTER.

SPECIFICATION forming part of Design No. 28,748, dated May 31, 1898.

Application filed April 27, 1898. Serial No. 679,043. Term of patent 7 years.

To all whom it may concern:

Be it known that I, JESSE K. PAINTER, a citizen of the United States, residing at Julesburg, in the county of Sedgwick and State of Colorado, have invented and produced a new and original Design for a Grass and Weed Cutter, of which the following is a specification, reference being had to the accompanying drawings, forming a part thereof, in which—

5 Figure 1 is a plan view of a grass and weed cutter embodying my design, and Fig. 2 is a side elevation of the same.

10 The leading feature of the design consists of a flat blade A, the edges whereof are bevelled at the upper surface. In outline the blade is provided with a rear edge B, formed upon the lines of a compound curve, the convexed portion being at the center and the concaved portions adjacent to the side edges of the

15 blade. The sides are formed each with a short

20

straight surface C, practically parallel with a line drawn from the front to the rear of the blade through the center. These straight surfaces C meet the converging surfaces D and D', which latter surfaces where they connect form a point E at the front center of the blade.

A minor feature of the design consists in a plate F located upon the blade at its upper face, centrally near the convexed portion of its rear edge, and in a handle G, which rises from the plate F and extends upwardly and rearwardly.

I claim—

The design for the grass and weed cutter, 35 herein shown and described.

JESSE K. PAINTER.
